UNITED STATES PATENT OFFICE.

CHARLES H. EDDY, OF ATTLEBORO, MASSACHUSETTS.

ICE-CREAM FREEZER.

1,152,496.

Specification of Letters Patent.

Patented Sept. 7, 1915.

Application filed May 19, 1914. Serial No. 839,608.

To all whom it may concern:

Be it known that I, CHARLES H. EDDY, a citizen of the United States, residing at Attleboro, in the county of Bristol and State 5 of Massachusetts, have invented certain new and useful Improvements in Ice-Cream Freezers, of which the following is a specification.

This invention relates to ice-cream freezers 10 and like devices, and has for one of its objects to provide a simply constructed device whereby a plurality of freezer devices may be simultaneously actuated and a corresponding variety of creams may be frozen at 15 the same time and by one actuating mechanism.

Another object of the invention is to provide a device of this character of improved construction and increased efficiency.

With these and other objects in view the invention consists in certain novel features of construction as hereinafter shown and described and then specifically pointed out in the claims; and in the drawings illustrative 25 of the preferred embodiment of the invention. Figure 1 is a sectional side elevation of the improved device. Fig. 2 is a plan view with the parts in section on the line 2—2 of Fig. 1. Fig. 3 is a transverse sectional elevation. Figs. 4 and 5 are enlarged perspective views of the holding brackets. Fig. 6 is an enlarged detached perspective view of a pair of the guide brackets.

Corresponding and like parts are referred 35 to in the following description and indicated in all the views of the drawings by the same reference characters.

The improved device comprises in general an actuating mechanism supported upon a 40 receptacle for the ice and for the freezer cans, and arranged to simultaneously actuate a plurality of the cans, whereby a corresponding plurality of creams of varying flavors or qualities may be produced simultaneously by one operating mechanism.

The tub or receptacle for the ice is represented conventionally at 10, and may be of any required shape or size and any required material, but if two of the freezer cans are 50 employed the tub will preferably be elliptical as shown, but if a greater number of cans are employed the tub will preferably be circular. For the purpose of illustration a tub constructed of staves secured by hoops indicated at 11 is shown and provided with a bottom 12, these parts being of the usual

construction. Supported upon the bottom 12 of the tub are steps 13 to receive the lower journal 14 of the freezer cans. Each of the freezer cans comprises a bottom member 15 from which the stud 14 extends, a cylindrical intermediate member 16 and a cap or closure 17, the latter held in position by bayonet slots indicated at 18 in the cap 17 engaging over pins 19 extending from the upper edge of the cylindrical member 16. The cans 16 and their attachments are precisely alike and the description of one will suffice for both.

Rising from the cap 17 is a sleeve 20 terminating at its upper end in a pinion 21, the pinion sleeve and cap being preferably integral as shown. Mounted for rotation through each of the sleeves 20 and its pinion 21 is a vertical shaft 22 which extends downwardly through the can and is stepped at 23 in the upper face of the bottom 15 of the can. The shaft 22 is circular where it passes through the sleeve 21 and square or in other form than round where it passes through the interior of the can, as indicated at 24. Slidably engaging each square portion of each shaft is a frame comprising end members 25 and vertically connecting side members 26, the members 26 being knife-edged and disposed tangentially to the interior of the can and to the shaft 22, as illustrated in Fig. 2. The members 25—26 being engaged upon the square portion 24 of the shaft are rotated by the shaft when the latter is re-

90 volved, as hereinafter explained. Directed outwardly from the connecting members 26 are small brackets 27 to which arms 28 are pivotally united at 29. The arms 28 extend toward the side walls of the can 16 and are formed with depending guide ribs 30 between which clearing blades 31 are supported. The arms 28 extend at their inner ends for engagement against the outer face of the blade members 26, as illustrated in 100 Fig. 2. By this means as the shaft 22 is rotated the frame 25—26 including its attachments will be rotated within the shell and the outer knife-edges of the blades 31 will scrape against the inner face of the can and being extended tangentially to the can 105 will turn the material toward the center, as will be obvious. The connecting members 26 being likewise inclined tangentially relative to the can will likewise scrape the material toward the center. Directed inwardly from the connecting members 26 are agi-

tators or mixing blades 32 which operate to thoroughly commingle and mix the ingredients as the device is operated.

Means are provided in the improved device for simultaneously rotating the cans in one direction and rotating the shafts 22 and their attachments in the opposite direction, thereby thoroughly mixing and commingling the ingredients, and this two-fold rotating mechanism is arranged to rotate both cans in the same direction and likewise to rotate both "beater" devices in the same direction, but opposite to the cans.

Mounted upon the upper outer face of the tub 10 at one side is a standard 33 having a transverse bearing rib or seat 34 and a socket 35, and likewise mounted upon the outer face of the tub or ice receptacle 10 at the opposite side is a similar standard 36 divided at the upper part to produce two vertical portions 37-38 spaced apart, and with a bearing seat or rib 39 extending across the divided portions and connecting them and likewise forming a seat which is disposed in transverse alignment with the seat 34 of the standard 33. Extending between the standards 33-36 and supported by the bearings 34-39 is an upper plate or frame member 40 having a bearing 41 at one end for engaging through the socket 35 of the standard 33 and reduced at the other end as represented at 42 to pass between the divided portions 37-38 of the standard 36. A button or similar holding device 43 is pivoted upon one of the spaced portions of the bracket 36, for instance the portions 37, and extends over the upper ends of the spaced portions and formed with a depending lip 44 at its free end and engaging over the outer face of the spaced standard portion 38 to hold the adjacent end of the member 40 from upward movement. By this arrangement the member 40 is held from downward movement by the bearings 34-39 and held from upward and lateral movement by the socket 35, the spaced members 37-38 and the button 43, while at the same time the member 40 and its attachments may be readily removed by simply releasing the button 43 and lifting the member 40 upwardly.

Depending from the member 40 is a supporting frame comprising a lower horizontal portion 45 and vertical side portions 46-47, the member 45 being secured in any suitable manner to the side portions 46-47. Extending laterally from the side portion 46 of the lower frame is a lug 48, while a similar lug 49 extends laterally from the portion 47 of the lower frame. Attached to the inner face of the tub 10 at opposite sides thereof are guide ribs 50-51 between which the lugs 48-49 are supported, and prevented thereby from lateral displacement. The ribs 50-51 and the lugs 48-49

thus coact with the standards 31-34 to firmly support the frame and prevent lateral displacement thereof, while at the same time permitting the frame to be readily removed from the tub and coupled thereto as required.

At their upper ends the shafts 22 are supported in bearings in the frame 40, and depending from the frame at its opposite ends are hoods 52-53. Stepped at 54 in the lower frame member 45 is a standard or support 55 having a transverse central bearing 56 to receive the inner end of a main drive shaft 57. The drive shaft extends between the spaced portions 37-38 of the bracket 36 and likewise through an open slot 58 in the receptacle 10, and is provided with an operating crank 59 at its outer end externally of the receptacle. Mounted for rotation upon the standard 55 at its upper end is a combined bevel and rim gear 60, while a similar combined bevel and rim gear 61 is mounted for rotation upon the lower end of the standard 55. A bevel pinion 62 is mounted upon the shaft 57 and engages the bevel portions of the gears 60-61. A pinion 63 is mounted upon each of the shafts 22 and engages with the rim portion of the gear 60, while the pinions 21 of the freezer cans engage with the rim portion of the gear 61. The pinions 63 are fixed upon the shafts 22 and rotated therewith, while the pinions 21 are loose upon the shafts. By this arrangement, it will be obvious, that when the shaft 57 is rotated by power applied to the crank 59 the pinion 62 will transmit the motion of the shaft continuously to the gears 60-61, in opposite directions and thence to the shafts 22 and the freezer cans, the shafts 22 and their attachments being rotated in the same direction while the freezer cans are rotated in the same direction but opposite to the rotation of the shafts. By this simple means, it will be obvious, that the freezer cans are simultaneously actuated in one direction, while the shafts 22 carrying the "beaters" will be rotated in the opposite direction, thereby applying a double motion to the compound to be frozen.

The improved device is simple in construction, can be strongly manufactured and by means of which two or more qualities or flavors of cream or like commodities may be frozen at the same time.

Having thus described the invention, what is claimed as new is:

1. In a device of the class described, a receptacle for the freezing medium, a plurality of freezing cans mounted for rotation in the said receptacle, a beater device mounted for rotation in each of said freezing cans, a standard having terminal bearings and a transverse bearing, a gear wheel mounted for rotation upon each of said terminal bearings, a gear pinion connected to each of

said freezing cans and engaging one of said gear wheels, a gear pinion connected to each of said beater devices and engaging the other gear wheel, a shaft mounted for rotation in the transverse bearing of said standard, and a gear pinion carried by said shaft and engaging said gear wheels, whereby the freezing cans and beater devices are rotated in opposite directions when motion is imparted to the shaft.

2. In a device of the class described, a receptacle for the freezing medium, a plurality of freezing cans mounted for rotation in said receptacle, a beater device mounted for rotation in each of said freezing cans and each including a vertical shaft, standards rising from said receptacle, a frame detachably supported in said standards and having bearings to receive said beater shafts,

15 a pinion carried by each of said beater shafts, a pinion carried by each of said freezing cans, a vertical standard carried by said frame, a gear pinion carried by said vertical standard and engaged by the pinions of said freezing cans, another gear pinion carried by the vertical standard and engaged by the

pinions of the beater shafts, and means for simultaneously rotating said gear pinions in opposite directions.

3. In a device of the class described, a receptacle for the freezing material, guide ribs spaced apart and carried by said receptacle, a plurality of freezing cans mounted for rotation in said receptacle, a beater device mounted for rotation in each of said freezing cans and each including a vertical shaft, a frame including a depending portion having laterally directed lugs detachably engaging said spaced ribs, means for detachably connecting said frame at its upper part to said receptacle, and means carried by said frame for simultaneously rotating said freezing cans in the same direction and for simultaneously rotating said beater devices in the opposite direction.

In testimony whereof I affix my signature in presence of two witnesses.
